Specification for Design.

Patented July 12, 1921.

Application filed December 23, 1920. Serial No. 432,870. Term of patent 14 years.

To all whom it may concern:

Be it known that I, SAMUEL HELLER, a citizen of the United States, residing at New York city, in the county and State of New York, have invented a new, original, and ornamental Design for a Precious, or Semiprecious, or Synthetic Stone, or an Imitation Thereof, or an Article of Similar Nature, of which the following is a specification, reference being had to the accompanying drawing, forming a part thereof.

In the drawings:

Figure 1 is a plan view of a cut stone embodying my design;

Fig. 2 is a side view thereof; and

Fig. 3 is an end view thereof.

I claim:

The ornamental design for a precious, or semiprecious, or synthetic stone, or an imitation thereof, or an article of similar nature, as shown.

In testimony whereof I affix my signature.

SAMUEL HELLER.
